CLAIM

The ornamental design for a portable monitor, as shown and described.

DESCRIPTION

FIG. 1 is a front, top perspective view of a portable monitor showing my new design;

FIG. 2 is a rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the figures are for the purpose of illustrating portions of the portable monitor that forms no part of the claimed design.

1 Claim, 8 Drawing Sheets
